US00D847174S

(12) **United States Design Patent** (10) **Patent No.:** **US D847,174 S**
(45) **Date of Patent:** **** Apr. 30, 2019**

(54) **DISPLAY SCREEN OR PORTION THEREOF WITH GRAPHICAL USER INTERFACE**

(71) Applicant: **Lutron Electronics Co., Inc.**,
Coopersburg, PA (US)

(72) Inventors: **Rhythm Agarwal**, Bethlehem, PA (US);
Benjamin F. Bard, Zionsville, PA (US);
Erica L. Clymer, Northampton, PA (US);
Jemma C. Robinson, Brooklyn, NY (US);
Sara M. Thompson, Brooklyn, NY (US);
Shenchi Tian, Easton, PA (US)

(73) Assignee: **Lutron Electronics Co., Inc.**,
Coopersburg, PA (US)

(**) Term: **15 Years**

(21) Appl. No.: **29/612,902**

(22) Filed: **Aug. 4, 2017**

(51) LOC (11) Cl. **14-04**

(52) U.S. Cl.

USPC **D14/486**

(58) **Field of Classification Search**

USPC **D14/485-495**

(57)

CLAIM

The ornamental design for a display screen or portion thereof with graphical user interface, as shown and described.

DESCRIPTION

The sole FIGURE shows a display screen or portion thereof with graphical user interface showing our new design. Shading represents tonal contrast.

The peripheral dashed broken lines illustrate a display screen or portion thereof, and form no part of the claimed design.

1 Claim, 1 Drawing Sheet
